FLEXIBLE SEAR MECHANISM FOR FIREARMS

Albert H. Tompkins, Springfield, Mass.

Application February 13, 1946, Serial No. 647,318

8 Claims. (Cl. 42—69)

1

This invention relates to firearms, and has for one object the improvement of the hammer or bolt release mechanism so as to give a steadier trigger pull than has heretofore been possible, and to cut to a minimum the motion of the trigger particularly at the point of release. A further object is to provide a trigger and sear mechanism in which the strength of pull may be regulated easily by a simple screw adjustment. A further object is to provide a trigger and sear mechanism of greater simplicity than former mechanisms, and which is less expensive to manufacture. A further object is to improve the breechblock to increase greatly the strength of the firearm. A further object is to provide improved automatic firing pin retracting mechanism operative upon the breechblock being opened. Additional objects will appear from the following description and claims.

The invention will now be described with reference to the accompanying drawings, in which:

Figs. 1 and 1A are collectively a side elevation of the arm;

Fig. 2 is a fragmentary side elevation with the breechblock open and the hammer cocked, and with some parts broken away to show the interior construction;

Fig. 3 is a similar view with the breechblock closed and the hammer in the rest position to which it returns after firing;

Fig. 4 is a detail of the sear and hammer in a position intermediate those of Figs. 2 and 3;

Fig. 5 is a side elevation with the breechblock closed, partially broken away in median section;

Fig. 6 is a top plan with the breechblock about to be opened;

Fig. 7 shows in median section the first stage in the opening of the breechblock;

Fig. 8 is a side elevation, partly broken away, of the same position as in Fig. 7;

Fig. 9 is a side elevation showing the first stage in closing the breechblock;

Fig. 10 is a section on line 10—10 of Fig. 11;

Fig. 11 is a section on line 11—11 of Fig. 10;

Fig. 12 is a section on line 12—12 of Fig. 3; and

Figs. 13 and 14 are modifications showing the use of the improved sear on two types of bolt action firearms.

The improved breechblock and sear mechanism is shown as applied for illustration to a single shot target pistol, but it is obvious that various features of the mechanism can be used in other settings. The main frame 1 which carries the operating parts of the arm is secured in any usual or desired way in a stock 2. This stock

preferably extends along the barrel and as shown in Fig. 1A is provided with a slot 4 to retain a weight for giving the desired balance to the arm. The barrel is shown (Fig. 2) as threaded into the frame at 5 and held by a pin or screw 6.

A breechblock indicated generically at 7 is formed in two major pieces, a block 8 and a locking or finger piece 9. The block 8 is hinged at 10 to the frame adjacent the barrel so that it can be swung upwardly to expose the barrel chamber. A firing pin 11 is slidable in a hole 12 in the block 8 directed so that the point 13 of the firing pin will strike the primer of the cartridge. A groove 14 in the firing pin receives the reduced end 15 of a set screw 16 threaded into the block 8, so that the firing pin may have the free motion needed for its operation but cannot fall out when the breechblock is open.

The rear of the side walls of the block 8 are formed with a vertical slideway such as vertical grooves 17 for the reception of a T-slot 18 in the finger piece 9 which in this way is made vertically slidable. One of the ribs 20 formed by the grooves 17 is cut away at 21 (Figs. 6, 8, 11 and 12) to receive freely the turned down end 22 of a set screw 23 secured in the finger piece 9. The finger piece is thus permitted a limited vertical sliding motion relative to the block 8. Normally the finger piece is held down on the same level as the block 8 by a bent spring 24 (Figs. 10 and 11) held by a screw 25 in a slot 26 formed in the block and having one end projecting into a recess 27 in the finger piece.

The frame 1 to the rear of the breechblock 35 is formed with two vertical surfaces 28 and 29 separated by a horizontal step 30. The frame is cut out with a central slot 31 to receive the hammer 32, there being a corresponding recess 33 in the finger piece 9 separated on a slant line 34 from a narrower recess 35 embracing slabbed off portions 36 of the firing pin 11 just back of its head 37. The back of this head is cut away at 38 to mate with the slanting surface 34, so that, as the finger piece is in raised position relative to the block, the firing pin will be withdrawn positively from its firing position. The hammer recess 31 does not extend to the top of the frame, leaving a cross bridge 39 which may serve as an abutment against which a shoulder 40 on the hammer may strike if the hammer is released with no cartridge in the chamber, thus preventing crystallization of the firing pin head if it is desired to practice with the arm in this condition.

The finger piece 9 acts both as a lock for the breechblock and as an extension of it to the abut-

ment surfaces 28 and 29 of the frame when the block is in its normal position of Fig. 5. For this purpose the finger piece has an upper vertical surface 41 separated by a shoulder 42 from a lower vertical surface. Referring to Fig. 5 it will be noted that the upper surface 41 is shorter than its mating surface 28 and that the lower surface 43 is shorter than its mating surface 29 so that a substantial space is left between the shoulders 30 and 42. When the breechblock is in closed position these pairs of surfaces act as abutments which transmit the force of the explosion to the frame. To disengage the breechblock the finger piece 9 is grasped and drawn upwardly. Initially both pairs of surfaces prevent any swinging movement of the breechblock, as any swinging movement would press the abutments more tightly together on account of the position of the hinge 10. The finger piece thus moves vertically and against its spring. When the finger piece has moved upwardly so that surface 41 moves beyond the top of surface 28 and surface 43 moves beyond shoulder 30 swinging movement of the breechblock is permitted and the block 8 will catch up with the finger piece on account of its spring connection. In order to avoid binding the lower pair of abutting surfaces are preferably made of slightly less height than the upper pair; as the upper surface 41 is, by reason of its horizontal alignment with pivot 10, moving almost parallel to the surface 28 at the instant of disengagement.

Locking of the breechblock is accomplished by pressing downwardly on the block 8 rather than on the finger piece which, as shown in Fig. 9, initially comes to a position against shoulder 30 where it is incapable of downward movement. The block is, however, free to move downwardly on account of the spring connection and assumes more and more a horizontal position with the finger piece remaining elevated but tending towards the position of Fig. 7. As soon as this position is reached the lower surface 43 clears the shoulder 30 and the finger piece is shot downwardly by the spring. The breechblock is now locked and can be freed only by pulling upwardly on the finger piece.

The hammer 32 is pivoted to the frame at 44 and has a front pin 45 and a rear pin 46 each extending laterally outwardly at each side. The usual spacing sleeves 47 on the pivot maintain the hammer centralized. The mainspring 48 is of hairpin shape with its loop extending around a screw 49 and between its washer 50 and the frame. The two sides of the hairpin straddle the hammer and overlie the pins 45 and 46. Pin 45 tensions the mainspring as the hammer is drawn to cocking position and is acted on by the spring to drive the hammer into firing position upon release. Pin 46 is set to make contact with the spring on the rear side of the pivot just before the hammer reaches firing position and serves to return the hammer to a neutral position free of the firing pin.

The hammer is provided with a sear notch 51 to engage the end of the sear 52 which is in the form of a flat spring looped around a pin 53. The sear rests against a pin 54 between pin 53 and the hammer and is pressed against the hammer by a flat sear spring 55 clamped to the frame by a screw 56. To adjust the force with which the sear is held to the hammer, and thus the pull of the trigger required for release, a set screw 57 is threaded through the frame so as

10 to be accessible when the breechblock is swung up (Fig. 2) and to bear against the upper surface of the sear spring. The trigger 58 is pivoted at 59 to the frame and has a forwardly projecting nose 60 adjacent which is a short flat spring 61 held to the trigger by a screw 62. The trigger nose and the spring 61 fit together into a recessed block 63 screwed or riveted to the sear, the spring 61 acting merely to prevent any lost motion between the sear and trigger.

15 The cocked position of the parts is shown in Fig. 2. The sear is pressed into the sear notch by the spring 55 but is otherwise unstressed. As the trigger is drawn back the portion of the sear between pins 53 and 54 is fixed downwardly against, of course, progressively increasing resistance. The flexing of this part of the sear gives to the portion between pin 54 and the hammer a tendency to bend upwardly which is resisted both by its engagement with the sear notch and by the sear spring 55. This flexing of the sear is accomplished with such slight movement of the trigger as to be practically imperceptible, the feel being that of increasing pressure rather than movement. This is particularly noticeable when the sear finally springs free of the sear notch, since the motion is practically confined to the end portion of the sear beyond pin 54 and is not apparent at the trigger. 20 There being no jumping of the trigger at the instant of firing, much greater accuracy is possible as has been shown by the use by experts of a target pistol constructed as above.

25 The sear mechanism is equally adapted to other types of arm. Figs. 13 and 14 show its use on two types of bolt action in which the respective sears 64 and 65 are flexed upwardly between pins 66 and 67 and rest pins 68 and 69. In Fig. 13 a rocker 70 is interposed between the trigger 71 and the sear, while in Fig. 14 the trigger 72 is provided with a heel 73 on the rear side of the trigger pivot. In both cases the trigger when pulled causes the sear to be flexed upwardly, pulling its free end downwardly to release the bolt 74 or 75. Other adaptations to specific types of bolt or hammer actions will readily suggest themselves from the above description.

30 I claim:

1. In a firearm, a firing member provided with a sear engaging abutment, a spring actuating said firing member, a flexible sear pivoted at one end, its second end engaging said abutment to hold said member against actuation by said spring, a second abutment positioned intermediate the ends of the sear and engaging that side of the sear which faces the firing member, a trigger and trigger operated means for flexing the sear between its pivot and said second abutment in a direction to flex its second end out of engagement with the abutment on the firing member.
2. In a firearm, a firing member provided with a sear engaging abutment, a spring actuating said firing member, a flexible sear pivoted at one end, its second end engaging said abutment to hold said member against actuation by said spring, a second abutment positioned intermediate the ends of the sear and engaging that side of the sear which faces the firing member, a spring engaging the sear adjacent its second end to press the latter against said firing member, a trigger and trigger operated means for flexing the sear between its pivot and said second abutment in a direction to flex its second end out of engagement with the abutment on the firing member.

3. In a firearm, a firing member provided with a sear engaging abutment, a spring actuating said firing member, a flexible sear pivoted at one end, its second end engaging said abutment to hold said member against actuation by said spring, a second abutment positioned intermediate the ends of the sear and engaging that side of the sear which faces the firing member, a spring engaging the opposite side of the sear adjacent its second end to press the latter against the firing member, means for adjusting the tension of the last named spring, a trigger and trigger operated means for flexing the sear between its pivot and said second abutment in a direction to flex its second end out of engagement with the abutment on the firing member.

4. In a firearm having a pivoted hammer having a sear notch, a spring stressing the hammer for movement toward firing position, a flexible sear pivoted at one end and at its other end engaging the sear notch to hold the hammer in cocked position, an abutment engaging the sear intermediate its ends to prevent its movement in a direction toward the hammer, a trigger and trigger operated means for flexing the sear between its pivot and the abutment in a direction to flex its second end out of engagement with the sear notch.

5. In a firearm having a pivoted hammer having a sear notch, a spring stressing the hammer for movement toward firing position, a flexible sear pivoted at one end and at its other end engaging the sear notch to hold the hammer in cocked position, an abutment engaging the sear intermediate its ends to prevent its movement in a direction toward the hammer, a spring engaging the second end of the sear to press it into the sear notch, a trigger and trigger operated means for flexing the sear between its pivot and the abutment in a direction to flex its second end out of engagement with the sear notch.

6. In a firearm having a pivoted hammer having a sear notch, a spring stressing the hammer for movement toward firing position, a flexible sear pivoted at one end and at its other end engaging the sear notch to hold the hammer in cocked position, an abutment engaging the sear intermediate its ends to prevent its movement in a direction toward the hammer, a spring engaging the second end of the sear to press it into the sear notch, means for adjusting the tension of the last named spring, a trigger and trigger

operated means for flexing the sear between its pivot and the abutment in a direction to flex its second end out of engagement with the sear notch.

5 7. In a firearm having a pivoted hammer having a sear notch, a spring stressing the hammer for movement toward firing position, a flexible sear pivoted at one end and at its other end engaging the sear notch to hold the hammer in cocked position, an abutment engaging the sear intermediate its ends to prevent its movement in a direction toward the hammer, a flat spring secured at one end and engaging the second end of the sear to press it into the sear notch, a trigger and trigger operated means for flexing the sear between its pivot and the abutment in a direction to flex its second end out of engagement with the sear notch.

8. In a firearm having a pivoted hammer having a sear notch, a spring stressing the hammer for movement toward firing position, a flexible sear pivoted at one end and at its other end engaging the sear notch to hold the hammer in cocked position, an abutment engaging the sear intermediate its ends to prevent its movement in a direction toward the hammer, a flat spring secured at one end and engaging the second end of the sear to press it into the sear notch, a screw adjustably engaging said flat spring intermediate its ends to regulate its pressure against the sear, a trigger and trigger operated means for flexing the sear between its pivot and the abutment in a direction to flex its second end out of engagement with the sear notch.
